UNITED STATES PATENT OFFICE

LEWIS J. BAZZONI, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

HEEL-COVER-TRIMMING MACHINE

Application filed May 4, 1929. Serial No. 360,529.

This invention relates to machines for trimming heel coverings and is herein illustrated as embodied in a machine for trimming coverings attached to heels to prepare the marginal portions of the coverings for insertion in grooves in the breasts of the heels.

In covering ungrooved Cuban heels it is generally the practice to cover the rear portion and the sides of the heel with one piece of covering material and to turn the forward marginal portions of the covering over the breast corners of the heel and adhesively to secure them to the breast of the heel in such a manner that one of the marginal portions will overlap the other, the seam formed between the overlapping marginal portions of the covering being located approximately at the central portion of the breast. There are certain disadvantages in heels covered as described above, one being that the seams formed by the overlapped portions of the coverings are likely to break open and thus detract from the appearance of the shoe.

In order to overcome this disadvantage and to provide durable heels which are neat in appearance, certain improved features of covered heel construction have been disclosed and claimed in United States Letters Patent Nos. 1,704,204 and 1,718,177 issued March 5, 1929, and June 18, 1929, respectively, on applications filed in the name of William H. Nutt. As fully explained in Patent No. 1,718,177, a heel is provided having a groove in the centre of its breast and extending generally height-wise of the heel, into which groove a one-piece covering stretched over and conforming to the rear, sides and breast surfaces of the heel has its marginal portions inserted and secured therein. As set forth in the above-mentioned Letters Patent No. 1,704,204, relatively narrow grooves are made in the breast of the heel adjacent to the breast corners so as to form a rib extending along each marginal portion of the breast of the heel. In covering a heel in this manner, a covering for the rear and the sides of the heel is applied with its forward marginal portions covering the rib on the heel breast and inserted into and secured within the grooves at the inner sides of the rib, the portions of

the breast surface between the ribs being covered with a separate covering.

In covering heels of the improved type above referred to, it will be obvious that the marginal portions of the side covering should be trimmed accurately in order to have the side covering fit properly in the grooves. It is quite difficult accurately to trim the marginal portions of these coverings by hand and such process is slow and requires a high degree of skill on the part of the operator.

An object of the present invention is to provide a reliable machine for expeditiously trimming the coverings of heels for reception in grooves in the breasts of the heels.

With the above object in view and in accordance with a feature of the invention, the illustrated machine is provided with instrumentalities illustrated as a disk cutter to trim a marginal portion of a covering attached to a heel for preparing that portion for insertion in a groove in the breast of the heel and means to position the heel and the marginal portion of the covering relatively to the trimming instrumentalities, the trimming instrumentalities and the means for positioning the heel being mounted for relative movement to carry out the heel trimming operation.

In accordance with another feature of the invention, the illustrated machine is provided with a table for supporting the marginal portion of the covering and having a gage fixed thereto, which gage is constructed and arranged to engage within the groove to position the heel relatively to the table. In order to position the marginal portion of the covering upon the table and to retain the same so positioned as the trimming operation progresses, the table carries a holdown device arranged for movement toward and away from the table to press the marginal portion of the covering against the table and against the breast of the heel. In accordance with a further feature of the invention, the illustrated machine is provided with a guideway constructed and arranged for determining the path of movement of the heel positioned upon the table past the rotary cutter to trim the marginal portion of the covering attached to the heel.

With the above and other objects in view the invention will now be described in connection with the accompanying drawings and pointed out in the claims.

Fig. 1 is a side elevational view of the illustrated heel covering trimming machine showing a heel presented thereto for preparing a marginal portion of its side covering for insertion in a groove in the center of the breast of the heel;

Fig. 2 is a perspective view of the machine and the heel shown in Fig. 1;

Fig. 3 is an enlarged perspective view of the machine fitted for trimming the marginal portions of the side covering of heels for insertion in curved grooves in the breasts of the heels and adjacent to the breast corners of the heels, portions of the machine being broken away more clearly to illustrate the heel positioning and trimming instrumentalities; and

Fig. 4 is a perspective view of a portion of the machine, part of which has been broken away to show a section taken along the line IV-IV of Fig. 3 and illustrating a heel in the process of having the marginal portion of its side covering trimmed in the machine for preparing the same for insertion in a groove following a breast corner of the heel.

The illustrated heel-cover trimming machine includes a disk or rotary cutter 10 for trimming a covering 12 to prepare it for insertion in either one of two forms in grooves 14 (Figs. 1 and 2), 16 (Fig. 4) in the breast of a heel 18, gages 20 (Figs. 1 and 2) and 22 (Figs. 3 and 4) constructed and arranged to engage within the grooves 14 and 16 respectively to position the heel 18 relatively to the disk cutter 10, a table 26, which carries either one of the gages 20, 22, for supporting the marginal portion 24 of the covering and a holddown device 28 to position the marginal portion 24 of the covering upon the table 26 for presenting the same to the cutter 10, the table 26 together with either of the gages 20 and 22 and the holddown device 28 being mounted for movement past the cutter 10 for carrying out the trimming operation.

The above-referred to instrumentalities for facilitating the positioning of the heel 18 and the marginal portion 24 of the heel covering relatively to the cutter 10 and for trimming the covering are supported upon a standard 30 including a bracket 32 secured thereto by screws 34 (Figs. 1 and 4), which bracket carries a plate 36 clamped to its forward end (Fig. 2). For conveniently raising or lowering the heel positioning instrumentalities the plate 36 is mounted for adjustment in a vertical direction relatively to the standard 30, the plate 36 being held in the desired vertical position by a bolt 38 which is screwed into the bracket 32 and passes through a slot 40 in the plate 36. In order to prevent lateral shifting between the bracket 32 and the plate

36 as the above-described vertical adjustment is effected, the bracket 32 is provided with a vertically extending recess 42 for receiving a tongue portion 44 of the plate 36. The upper forward portion of the plate 36 includes a horizontally disposed dove-tail tenon 46 which is constructed and arranged to mate with a dove-tail mortise portion 48 (Fig. 4) in a depending flared portion 50 of the table, thus providing a guideway for slidably supporting the table as it is moved past the rotary cutter 10 to carry out the trimming operation, which will later be described.

The cutter 10 is mounted upon the end of a shaft 52 by a screw 54, the shaft being supported for rotation in any conventional manner in the upper portion of the standard 30.

The table 26 upon which the marginal portion 24 of the heel covering is supported at opposite sides of the cutter 10 as the trimming operation progresses, comprises a horizontal portion 56 and the depending flared portion 50 by which it is supported and guided as above described. In order to assure a snug sliding fit between the mortise portion 48 of the table 26 and tenon portion 46 of the plate 36 the table is provided with a gib 58 (Fig. 4) which may be conveniently adjusted by the screws 60. The central portion of the table has a recess 62 extending therethrough for conveniently disposing of the surplus trimmings. The portion of the table upon which the marginal portion 24 of the covering is presented to the cutter 10 preferably consists of a composite pad 64 of a relatively soft material which is held in position and is easily replaceable upon the horizontal portion 56 of the table by the screws 66. The composite material 64 may be integral with the table 26 and for purposes of illustration will be considered as part of the table.

In order to position the heel 18 relatively to the table 26 and the cutter 10, the machine is provided with the gages 20, 22 secured to the table 26 by screws 68 (Fig. 1), 66 (Fig. 4), respectively, the type of gage used depending upon whether it is desired to trim the marginal portion 24 of the covering for insertion into the groove 14 which is positioned in the center of the breast of the heel and lies in a single plane or for insertion into the curved grooves 16 in the breast of the heel and substantially parallel to the breast corners of the heel. It will be noted that the gage 20 is secured to the table near the lower surface 72 thereof and that the gage 22 is clamped between the composite pad 64 and the horizontal portion 56 of the table. Since the center groove 14 lies in a single plane the gage 20 which engages within that groove may be of considerable length so that it extends beyond the attaching face and the top-lift-attaching face of the heel as shown in

Fig. 2. The length of the flat heel engaging portion 76 (Fig. 4) of the gage 22 however is quite short in order to provide for its insertion in the curved groove 16, the engaging portion 76 having sufficient length to position effectively the heel 18 relatively to the table 26.

To position the marginal portion 24 of the covering upon the table 26 and to retain the same so positioned thereon as the table is moved past the cutter 10, the machine is provided with the holddown device 28 movable toward and away from the table 26 upon a rod 78 which extends through a portion of the table 26 and is secured against movement relatively to the table in the direction of its axis. The holddown device 28 which is thus arranged for movement with the table includes the elongated bar 79 L-shaped in cross-section attached to an arm 80 which is secured at 82 to the rod 78 for moving the bar 79 toward and away from the table 26 as above stated. The bar 79 is constructed and arranged to press the marginal portion 24 of the covering against the table 26 and against the breast of the heel (Figs. 1 and 4) when the heel 18 has been positioned upon either of the gages 20, 22.

It will be noted that in trimming the marginal portions 24 of the coverings for the two types of grooved heels above described that the bar 79 engages the coverings against different portions of the breasts of the heels. In center groove work, such as shown in Figs. 1 and 2, the flange 84 of the bar 79 engages the covering upon the heel breast at 86 (Fig. 1) to position the heel covering relatively to the table 26, while in the curved groove work, such as shown in Figs. 3 and 4, the flange 88 (Figs. 3 and 4) of the bar 79 engages the covering upon the breast of the heel near one of the breast corners of the heel while positioning the marginal portion of the heel covering relatively to the table 26. In order conveniently to operate the holddown 28 and to move the table 26 past the cutter 10, the rod 78 is provided with a curved end portion 90 (Figs. 1 and 2) upon the end portion of which is mounted a handle 92. The sliding movement of the table 26 upon the tenon portion 46 of the plate 36 is limited by a screw 93 (Fig. 1) and a pin 95 fixed to the plate 36.

To protect the operator during the heel trimming operation, the machine is provided with a guard 94 pivotally mounted upon an arm 96 which has a slot 98 (Fig. 2) arranged to receive a bolt 100 threaded into the top of the standard 30 for adjustably securing the guard 94 in the desired position relatively to the cutter 10. The guard 94 is normally held in its rear position (Figs. 1 and 2) by a spring 102 the end portions of which are secured to the studs 104, 106 of the arm and the guard, respectively.

In operating the machine for trimming the

marginal portion 24 of the covering for insertion in either of the grooves 14, 16 the heel is presented to the table 26, the gages 20 and 22 engaging within the grooves 14 and 16 respectively, and the marginal portion 24 of the covering lying upon the top of the table 26 which may be said to be interposed between the heel 18 and the marginal portion 24 of the covering. The bar 79 of the holddown device 28, which bar up until now has been held some distance above the supporting surface of the table is now lowered to a position so that it slightly clears the marginal portion 24 of the covering upon the table 26. If necessary the heel is slightly adjusted upon one of the gages 20, 22 so that the bar 79 presses lightly against the covering upon the breast of the heel. When the heel and the marginal portion 24 of the covering have been correctly positioned, the bar 79 is moved toward the table to press the marginal portion of the covering against the table and against the breast of the heel as shown in Figs. 1 and 4. The heel 18 and the marginal portion 24 of the covering thus positioned are then moved past the cutter 10, the operator gripping the handle 92 which also is used in operating the holddown device 28.

Having thus described my invention, what I claim as new and desire to secure by Letters Patent of the United States is:

1. A machine for trimming heel coverings having, in combination, means to trim a marginal portion of a covering attached to a heel to prepare said portion for insertion in a groove in the breast of the heel, and means to position the heel and the marginal portion of the covering relatively to the trimming means, the trimming means and the last-named means being mounted for relative movement progressively to carry out the heel trimming operation.

2. A machine for trimming heel coverings having, in combination, a cutter for trimming a covering attached to a heel to prepare a marginal portion of the covering for insertion in a groove in the breast of the heel, and means to position the marginal portion of the covering, said means and cutter being mounted for relative movement progressively to carry out the trimming operation while the marginal portion of the covering is so positioned.

3. A machine for trimming heel coverings having, in combination, a cutter for trimming a covering attached to a heel to prepare a marginal portion of the covering for insertion in a groove in the breast of the heel, and means including a holddown device for supporting the marginal portion of the covering, said means and cutter being mounted for relative movement to carry out the trimming operation while the said marginal portion of the covering is supported.

4. A machine for trimming heel coverings having, in combination, a cutter for trimming

a covering attached to a heel to prepare a marginal portion of the covering for insertion in a groove in the breast of the heel, means for supporting the marginal portion of the covering, and means for clamping the said marginal portion of the covering upon the supporting means, said means and cutter being mounted for relative movement to carry out the trimming operation while the said marginal portion of the covering is supported.

5. A machine for trimming heel coverings having, in combination, means to trim a marginal portion of a covering attached to a heel to prepare the covering for insertion in a groove in the breast of the heel, and means to position the heel and the marginal portion of the covering relatively to the trimming means, said last-named means being mounted for movement past the trimming means to carry out the trimming operation.

6. A machine for trimming heel coverings having, in combination, a cutter to trim a marginal portion of the covering attached to a heel to prepare a marginal portion of the covering for insertion in a groove in the breast of the heel, and a member constructed and arranged to provide a rest for the marginal portion of the covering and being interposed between the heel and the marginal portion of the covering to position the covering relatively to the cutter, said cutter and member being mounted for relative movement to carry out the trimming operation.

35. 7. A machine for trimming heel coverings having, in combination, a cutter to trim a covering attached to a heel to prepare a marginal portion of the covering for insertion in a groove in the breast of the heel, a support arranged to be interposed between the heel and the marginal portion of the covering therefor to provide a rest for the marginal portion of the covering, a heel positioning gage carried by the support and arranged to engage within the groove, and means to position the marginal portion of the covering relatively to the support and the cutter, said cutter and support being mounted for relative movement to carry out the trimming operation.

8. A machine for trimming heel coverings having, in combination, a cutter to trim a covering attached to a heel to prepare a marginal portion of the covering for insertion in a groove in the breast of the heel, a heel positioning member arranged to be interposed between the heel and the marginal portion of the covering to provide a rest for the covering and to facilitate the positioning of the heel relatively to the cutter, and means to position the covering upon the member, said cutter and member being mounted for relative movement to carry out the trimming operation.

9. A machine for trimming heel coverings

having, in combination, a cutter to trim a covering attached to a heel to prepare a marginal portion of the covering for insertion in a groove in the breast of the heel, and a member arranged to be interposed between the heel and covering to be trimmed, said member providing a rest at opposite sides of the cutter for the covering to be trimmed, the cutter and the member being mounted for relative movement to carry out the heel trimming operation.

10. A machine for trimming heel coverings having, in combination, a cutter to trim a covering attached to a heel to prepare a marginal portion of the covering for insertion in a groove in the breast of the heel, a member arranged to be interposed between the heel and marginal portion of the covering to provide a rest for the marginal portion of the covering at opposite sides of the cutter and against the thrust of the cutter, and means to position the covering upon the member, said cutter and member being mounted for relative movement to carry out the heel trimming operation.

11. A machine for trimming heel coverings having, in combination, means to trim a covering attached to a heel for preparing a marginal portion of the covering for insertion in a groove in the breast of the heel, a heel positioning gage constructed and arranged to engage within the groove, a member arranged to support said marginal portion of the covering, and a device to position the covering upon the member relatively to the trimming means, said gage, member and device being mounted for movement past the trimming means.

12. A machine for trimming heel coverings having, in combination, a cutter to trim a covering attached to a heel for preparing a marginal portion of the covering for insertion in a groove in the breast of the heel, a heel positioning gage constructed and arranged to engage within the groove, a table to support said marginal portion of the covering, and a hold-down device to position the covering upon the table relatively to the cutter, said table being mounted for movement relatively to the cutter to move the covering positioned upon the table past the cutter to carry out the trimming operation.

13. A machine for trimming heel coverings having, in combination, a cutter to trim a covering attached to a heel for preparing a marginal portion of the covering for insertion in a groove in the breast of the heel, a heel positioning gage constructed and arranged to engage within the groove, a table to support said marginal portion of the covering, and a hold-down device to position said portion of the covering upon the table and to retain the same in position thereon, the cutter and the table being mounted for rela-

tive movement to carry out the trimming operation.

14. A machine for trimming heel coverings having, in combination, a cutter to trim a covering attached to a heel to prepare a marginal portion of the covering for insertion in a groove in the breast of the heel, a heel positioning gage constructed and arranged to engage within the groove, a table to support said marginal portion of the covering, and a holdown device to position said portion of the covering upon the table and to retain the same in said position, said table being movable relatively to the cutter to permit the heel thus positioned upon the table to be moved in a rectilinear path past the cutter to carry out the trimming operation.

15. A machine for trimming heel coverings having, in combination, a cutter to trim a covering attached to a heel for preparing a marginal portion of the covering for insertion in a groove in the breast of the heel, a table to support said marginal portion of the covering, a heel positioning gage fixed to the table, and a holdown device to position said portion of the covering upon the table, said table being mounted for movement relatively to the cutter to carry out the trimming operation.

16. A machine for trimming heel coverings having, in combination, a cutter for trimming a covering attached to a heel to prepare a marginal portion of the covering for insertion in a groove in the breast of the heel, a table to support said marginal portion of the covering, and a heel positioning gage fixed to the table constructed and arranged to engage within the groove, said table being mounted for movement relatively to the cutter to carry out the trimming operation.

17. A machine for trimming heel coverings having, in combination, a cutter to trim a covering attached to a Cuban heel to prepare a marginal portion of the covering for insertion in a groove in the breast of the heel, a table to support said portion of the covering, a heel positioning gage attached to the table and constructed and arranged to engage within the groove, and a holdown device to position said portion of the covering relatively to the table, said table together with the holdown device being mounted for movement relatively to the cutter to carry out the trimming operation.

18. A machine for trimming heel coverings having, in combination, a cutter for trimming a covering attached to a Cuban heel to prepare a marginal portion of the covering for insertion in a groove in the breast of the heel, a table to support the marginal portion of the covering, a heel positioning gage attached to the table and constructed and arranged to engage within the groove, and a holdown device constructed and arranged to press the marginal portion of the covering

against the table to position the said marginal portion of the covering upon the table relatively to the cutter, said table and holdown device being mounted for movement relatively to the cutter to carry out the trimming operation.

19. A machine for trimming heel coverings having, in combination, a cutter for trimming a covering attached to a Cuban heel to prepare a marginal portion of the covering for insertion in a groove in the breast of the heel, a table to support the marginal portion of the covering, a heel positioning gage attached to the table and constructed and arranged to engage within the groove, and a holdown device mounted for pivotal movement toward and away from the table to position said portion of the covering upon the table relatively to the cutter, said table being mounted for movement relatively to the cutter to carry out the trimming operation.

20. A machine for trimming heel coverings having, in combination, a cutter for trimming a continuation of a side covering attached to a Cuban heel to prepare a marginal portion of the covering for insertion in a groove in the breast of the heel, a table to support the marginal portion of the covering, a heel positioning gage constructed and arranged to engage within the groove, and means arranged to engage said marginal portion upon the table to position said portion upon the table relatively to the cutter, said table being mounted for movement relatively to the cutter to permit the moving of the covering thus positioned upon the table past the cutter to carry out the trimming operation.

21. A machine for trimming heel coverings having, in combination, a cutter for trimming a side covering attached to a Cuban heel to prepare a marginal portion of the covering for insertion in a groove in the breast of the heel, a support for the marginal portion of the covering, a heel positioning gage fixed to the support and constructed and arranged to engage within the groove, and means to position said marginal portion of the covering upon the support relatively to the cutter, said support being mounted for movement relatively to the cutter to carry out the trimming operation.

22. A machine for trimming heel coverings having, in combination, a cutter for trimming a side covering attached to a Cuban heel to prepare a marginal portion of the covering for insertion in a groove in the breast of the heel, a support for the marginal portion of the covering, a heel positioning gage fixed to the table and constructed and arranged to engage within the groove, and means arranged to press said marginal portion of the covering against the breast of the heel and against the support to position the same upon the table relatively to the cutter, said support

being mounted for movement relatively to the cutter to carry out the trimming operation.

23. A machine for trimming heel coverings having, in combination, a cutter for trimming a side covering attached to a Cuban heel to prepare a marginal portion of the covering for insertion in a groove in the breast of the heel, a support for the covering, a heel positioning gage fixed to the support and constructed and arranged to engage within the groove, and means mounted for pivotal movement toward and away from the support to position the marginal portion of the covering upon the support, said support being mounted for movement relatively to the cutter to carry out the trimming operation.

24. A machine for trimming heel coverings having, in combination, a rotary cutter for trimming a side covering attached to a Cuban heel to prepare a marginal portion of the covering for insertion in a groove in the breast of the heel, a table for supporting the covering, a heel positioning gage fixed to the table and constructed and arranged to engage within the groove, and a holddown device arranged to press a portion of the covering against the table to position said portion upon the table relatively to the cutter, said holddown device being pivotally mounted upon the table for movement toward and away from the table, said table being mounted for movement relatively to the cutter to carry out the trimming operation.

25. A machine for trimming heel coverings having, in combination, a cutter for trimming a covering attached to a heel to prepare a marginal portion of the covering for insertion in a groove in the breast of the heel, means to support the covering, heel positioning means constructed and arranged to engage within the groove, and means arranged to engage the marginal portion of the covering to position the same relatively to the supporting means, the cutter and said means being mounted for relative movement to carry out the trimming operation.

26. A machine for trimming heel coverings having, in combination, a cutter for trimming a marginal portion of a covering attached to a heel to prepare said portion for insertion in a groove in the breast of the heel, means to support the marginal portion of the covering, heel positioning means constructed and arranged to engage within the groove, and means arranged to press the marginal portion of the covering against the breast of the heel and the support to position the same relatively to the supporting means, the cutter and said means being mounted for relative movement to carry out the trimming operation.

27. A machine for trimming heel coverings having, in combination, a cutter to trim a marginal portion of a covering attached to a

heel for preparing said portion for insertion in a groove in the breast of the heel, means to support the marginal portion of the covering, heel positioning means constructed and arranged to engage within the groove, means arranged to press the covering against the breast of the heel and the support to position the same relatively to the supporting means, the cutter and said means being mounted for relative movement to carry out the trimming operation, and means to protect the operator from the trimming operation.

28. A machine for trimming heel coverings having, in combination, means to trim a marginal portion of a covering attached to a heel to prepare said portion for insertion in a groove in the breast of the heel, means to position the heel and the marginal portion of the covering relatively to the trimming means, the trimming means and the last-named means being mounted for relative movement to carry out the heel trimming operation, and means to protect the operator from the trimming means.

29. A machine for trimming heel coverings having, in combination, a cutter to trim a marginal portion of a side covering attached to a heel for insertion in a groove in the breast of the heel, a support for the marginal portion of the covering, a heel positioning gage constructed and arranged to engage within the groove, and means to cause the marginal portion of the covering to engage the breast of the heel to position said portion upon the support relatively to the cutter, said table being mounted for movement relatively to the cutter to carry out the trimming operation.

30. A machine for trimming heel coverings having, in combination, a cutter for trimming a marginal portion of a side covering attached to a heel for insertion in a groove of the breast of the heel, a table to support the marginal portion of the covering, a heel positioning gage fixed to the table and constructed and arranged to engage within the groove, and a holddown arranged to press the marginal portion of the covering against the breast of the heel and against the table to position the covering upon the table relatively to the cutter, said holddown being mounted for movement toward and away from the table, the table being mounted for movement relatively to the cutter to carry out the trimming operation.

In testimony whereof I have signed my name to this specification.

LEWIS J. BAZZONI.
